OIL AND WATER SEPARATOR HAVING A
COLLECTING PIPE AND A STRATIFI-
CATION PIPE THEREBELOWWalter L. Olivo and Joseph B. Terrell,
Denver City, Tex.

Application February 2, 1944, Serial No. 520,806

2 Claims. (Cl. 210—51)

1

This invention relates to oil and water separators and has reference, more in particular, to a so-called water "knock-out" trap for both pump-
er and pressure wells, and the principal object
is to generally and specifically improve upon pres-
ently known similarly constructed traps, this
through the adoption and use of a unitary con-
struction of utmost simplicity aptly and ideally
suited for the purposes intended.

Oil and water separators hitherto known are
rather complex structures usually provided with
a stratification chamber into which the oil mixed
with water enters. As the stratification chamber
of such a water trap can hardly have the requisite
height to exclude withdrawal of gas or water with
the oil, a standpipe, and oil, gas and water heads
have to be added from which the stratified fluids
may be withdrawn at levels sufficiently different
to prevent the withdrawal of more than one liquid
or fluid.

The present invention provides a simple and
more generally applicable water separator which
does not require a slowing down of the velocity
to a practical standstill.

According to the invention, an oil collection
pipe is used to which the oil mixed with water
is admitted and from which the oil, when en-
tirely freed from water, is withdrawn. This oil
pipe cooperates with a stratification pipe ar-
ranged below and communicating with it by
means of vertical pipes. It is provided with a
number of deflector partitions or baffles directing
the inflowing oil towards the stratification pipe
and reducing the velocity of the flow towards the
outlet. The oil pipe forms a straight communica-
tion between the inlet of the oil and its outlet.
The deflectors or baffles divide it into sections.
In the first section near the inlet end the oil and
the water carried by it is deflected into the stratifi-
cation pipe. The middle section is filled with
oil rising through the vertical pipes from the
stratification pipe. The deflecting baffle at the
end of this section directs any water which may
have been carried into this section by direct in-
flow or otherwise into the stratification pipe.
The latter, which is located in a separate branch,
permits complete stratification and separation
of the water and oil without causing emulsifica-
tion.

Another object of the invention is the provision
of a compact and convenient assemblage of co-
acting parts so designed and coordinated as to
minimize the presence of obstructive turns, this
to prevent the formation of emulsions, to main-
tain the desired uniform pressure and circulatory

2

action and insuring a steady and direct flow of
fluid from the time it enters the trap until it
leaves the trap by especially arranged discharge
devices.

5 Further, in carrying out the principles of the
invention the preferred structural embodiment
is such as to simplify the task of operation of
the attendant, to obviate the likelihood of the
component parts getting out of order and to pro-
10 mote safety by use of a well balanced adaptation
substantially free from blow-outs and break-
downs.

Other objects, features and advantages of the
invention will become more readily apparent from
15 the following description and the accompanying
illustrative drawings.

In the drawings, wherein like numerals are em-
ployed to designate like parts throughout the
views:

20 Figure 1 is an elevational view of the complete
trap construction showing how it is operatively
connected with a conventional oil well.

Figure 2 is an enlarged fragmentary section of
the intake chamber.

25 Figure 3 is a similar fragmentary sectional view
of the oil discharge chamber.

In the modification of the invention, as illus-
trated, the separator unit 30 for separating oil,
water and sand consists mainly of two chambers
30 formed by pipes 12 and 15 which are arranged
one below the other, and are connected by a num-
ber of vertical tubes and standpipes 14, 21, 21a,
22 and 19. Into this unit the oil from the well,
which is mixed with water and sand, is fed from
35 the well tube 4 leading from the well which is
provided with a head 5 connected with a tube
6 provided with a valve 7. This tube is, in its
turn, connected with an admission pipe 9 which
leads to the upper pipe 12 of the unit 30 forming
40 the oil collecting pipe. The admission pipe 9 may
be connected with the pipe 6 by means of a fitting
carrying a pressure gauge 8.

The admission pipe 9 is connected with the
intake nipple 10 of the oil collecting pipe 12 which
45 is of reduced cross section and which opens into
an admission chamber 11 formed within the oil
collecting pipe 12 at its entrance or admission end
by means of a deflector baffle 13 which fills part of
the cross section of pipe 12 but leaves the upper
50 part open for communication of the chamber
11 with the remainder of the pipe 12 as seen in
Figure 2. In front of the deflector baffle the main
vertical separator duct 14 is arranged, which con-
nects the oil collecting pipe 12 with the lower
55 or stratification pipe 15. It will be noted that

the deflecting baffle 13 is somewhat forwardly inclined and may be suitably curved. It thus faces the incoming jet entering under pressure through the restricted cross section at the end of the pipe 12 and being placed directly behind the main vertical duct 14, it will deflect the said jet and cause it to flow downwardly through the said main duct 14 into the stratification pipe 15.

The stratification pipe 15 is longer and of greater diameter than the oil collecting pipe 12 and it is moreover inclined with respect thereto and with respect to the horizontal.

Near the discharge end of the oil collecting pipe a discharge chamber 16 is formed by means of another baffle 20, partly filling the cross section of the tube and arranged directly behind another vertical connecting pipe 19 leading from the oil collecting pipe 12 to the stratification pipe 15. This discharge chamber 16 ends in a reducing nipple 17 to which the oil discharge pipe 18 is connected. The latter leads to a so-called flow beam or sampling case 26 provided with a valve or sampling cock 27 from which samples of the oil flowing to the clean oil or flow line 25 and to the battery of storage tanks may be taken, in order to check up on the operation of the separator.

At longitudinally spaced points between the two main ducts 14 and 9 connecting the oil collecting and stratification pipes 12 and 15, a number of auxiliary standpipes 21, 21a, 22 is arranged. They gradually increase as regards their vertical length on account of the inclination of the stratification pipe towards the horizontal. On account of this inclination the aft part of the stratification pipe will be filled mainly with water and sand, the latter sinking and being carried to the outlet end of the stratification pipe which is located at the lowest point. At this point a drain or dump pipe 24 is arranged for carrying off the water and sand to a suitable place of deposit. This pipe may be provided with a valve 23.

The entire unit 30 may be supported by means of suitable supporting stands 28, 29.

In operation the incoming column of fluid enters the chamber 11 of the oil collecting pipe 12 and is deflected by the deflecting baffle 13 down through the duct 14 into the intake end of the stratification pipe 15. Here the sand gravitates to the bottom and the oil floats on the top of the water. The sand and water follow the arrows A while the oil on top backs up and is elevated through the pipes 21, 22 and 19 into the oil collecting pipe 12 as indicated by the arrows B.

As the number of turns in the construction is reduced to a minimum there is virtually no likelihood of an emulsification of oil and water after it enters the trap. The use of simple baffle plates permits to arrange the inlet pipe, the oil collecting pipe and the discharge pipe at the same level in a straight line, eliminates the necessity for reducing the pressure to the zero level at the entrance or at the discharge end reduces the velocity of the flow through the oil collecting pipe and prevents the water which may have penetrated into the oil collecting pipe from getting into the discharge chamber. The elimination of emulsions of oil and water in this construction maintains a higher point of gravity of the oil. The latter will therefore be lowered as a result of separation in this construction.

Persons skilled in the art to which the invention relates will be able to make changes in the shape, size and arrangement of details coming

within the field of invention claimed without departing from the essence of the invention, as the principles underlying our invention have been clearly described in such terms as to indicate the essential points of the invention.

Having described the invention, what is claimed as new is:

1. An oil and water separator comprising an oil collecting pipe, an admission pipe and an oil discharge pipe, both directly connected with the oil collecting pipe and arranged at substantially the same level, a stratification pipe arranged below the oil collecting pipe, serving as a stratification chamber, a plurality of connecting pipes between said oil collecting pipe and said stratification pipe, one of these pipes being arranged near the end of the oil collecting pipe connected with the oil admission pipe and another near the end connected with the oil discharge pipe, and deflecting baffles in said oil collecting pipe arranged directly behind the two last named connecting pipes.

2. An oil and water separator comprising an oil collecting pipe extending in a horizontal direction and divided into three chambers, communicating with each other, two deflecting baffles inclined toward the axis of the oil collecting pipe filling a portion of its cross section, said partitions being arranged near the end portions of the oil collecting pipe forming an admission and discharge chamber and a central chamber, an admission pipe of restricted cross section in communication with said admission chamber, a discharge pipe in communication with said discharge chamber, a stratification pipe of a diameter, larger than the oil collecting pipe arranged below said oil collecting pipe in inclined position with respect to the same, a main separator duct leading from said admission chamber to said stratification pipe arranged directly in front of the deflecting baffle of said chamber, a second vertical connecting pipe leading from the stratification chamber to said central chamber arranged directly in front of the deflecting baffle of the discharge chamber and a discharge pipe for water and sand connected with the lower end of the stratification pipe.

25 3. An oil and water separator comprising an oil collecting pipe extending in a horizontal direction and divided into three chambers, communicating with each other, two deflecting baffles inclined toward the axis of the oil collecting pipe filling a portion of its cross section, said partitions being arranged near the end portions of the oil collecting pipe forming an admission and discharge chamber and a central chamber, an admission pipe of restricted cross section in communication with said admission chamber, a discharge pipe in communication with said discharge chamber, a stratification pipe of a diameter, larger than the oil collecting pipe arranged below said oil collecting pipe in inclined position with respect to the same, a main separator duct leading from said admission chamber to said stratification pipe arranged directly in front of the deflecting baffle of said chamber, a second vertical connecting pipe leading from the stratification chamber to said central chamber arranged directly in front of the deflecting baffle of the discharge chamber and a discharge pipe for water and sand connected with the lower end of the stratification pipe.
